UNITED STATES PATENT OFFICE.

LEMUEL S. HAINLINE, OF RUSHVILLE, MISSOURI.

DESIGN FOR A MONUMENT.

SPECIFICATION forming part of Design No. 31,161, dated July 4, 1899,

Application filed May 16, 1899. Serial No. 717,102; Term of patent 14 years.

To all whom it may concern:

Be it known that I, LEMUEL S. HAINLINE, a citizen of the United States, residing at Rushville, in the county of Buchanan and State of Missouri, have invented a new and useful Design for Monuments, of which the following is a specification.

Figure 1 represents a front elevation of my design. Fig. 2 represents a sectional view taken on the line II II of Fig. 1.

1 designates the representation of a closed door mounted in or surrounded by a Gothic headed door-frame 2. Immediately under the door is the representation of a raised scroll 3. The four corners of the shaft of the monument, also including the base of the shaft, together with the head of the shaft, is ornamented with the representation of Greek fretwork 4, as shown. The top of the shaft is mounted by a representation of a pyramidal cap. Immediately above the representation of the door on the shaft of the monument is the representation of a weeping-willow tree 6.

The main base of my design is ornamented with the representation of Greek fretwork 7, 25 the same as the shaft and as shown. The panel surrounded by the fretwork on the base is ornamented by the representation of a hanging festoon 5.

Mounted upon the base of my design and 30 upon which the shaft of the monument rests is a surbase 8, correspondingly copped or slanted to uniformly correspond with the top of the main base and the bottom of the shaft.

Having thus described the invention, what 35 I claim as new, and desire to secure by Letters Patent, is—

The design for a monument, as herein shown and described.

In testimony whereof I affix my signature 40 in the presence of two witnesses.

LEMUEL S. HAINLINE.
